(57) **CLAIM**

The ornamental design for a combined bag closure and hanger for shopping carts, as shown and described.

DESCRIPTION

FIG. 1 is a top plan view of the present invention with environmental structure shown in phantom (broken line).

FIG. 2 is a bottom plan view of the present invention with environmental structure shown in phantom (broken line).

FIG. 3 is a front view of the present invention, the opposite back plan view being a mirror image of the front with environmental structure shown in phantom (broken line).

FIG. 4 is a plan view of the left side of the present invention, the opposite right side plan view being a mirror image of the left side with environmental structure shown in phantom (broken line).

FIG. 5 is an elevated perspective view with environmental structure shown in phantom (broken line); and,

FIG. 6 is an elevated perspective view of the claim shown in an alternate position with environmental structure shown in phantom (broken lines).

The broken line showing of the shopping bag and shopping cart are included for the purpose of showing environmental structure and forms no part of the claimed design.

1 Claim, 6 Drawing Sheets
